UNITED STATES PATENT OFFICE.

WILLIAM L. McGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed October 1, 1919. Serial No. 327,754.

To all whom it may concern:

Be it known that I, WILLIAM L. McGRATH, a citizen of the United States, residing at Elmira, in the county of Chemung and State of New York, have invented certain new and useful Improvements in Engine Starters, of which the following is a specification.

My invention relates to an engine starter for the purpose of starting an engine such as an internal combustion engine, and the object thereof is to provide a simple, efficient and reliable device of this character in which the drive portion thereof is capable of being operated in the engaging operation of its driving member by hand or foot and of being automatically disengaged. According to the embodiment of my invention as herein shown, I employ a drive which includes certain features of the Eclipse-Bendix drive, but which differs therefrom in that the drive is not automatically engaged or meshed with the driving member of the engine as an incident to the starting of the motor, but is caused to be meshed by manual or foot operation, provision being also made for the automatic closing of the motor switch when the driving member or pinion has thus been placed in mesh with the engine member. By preference, the manual means in its initial movement effects a partial engagement or mesh between the driving member or pinion and the engine member whereupon complete engagement or mesh and final driving is automatically effected by the power of the motor which has been automatically started by the further movement of such manual means.

In the drawing Fig. 1 is a sectional elevation of a starting system embodying my invention; Fig. 2 a vertical section on the line 2—2 of Fig. 1; Fig. 3 a detail view of a modified form of construction; but omitting the switch such as is shown in Fig. 1; and Fig. 4 an elevation partly in section of a clutch used in said modification.

The structure illustrated in the drawings is selected as one embodiment of my invention, but it will be understood that such embodiment thereof may partake of different forms without departing from the spirit and scope of such invention. Moreover while I have shown the single reduction or direct type of drive from the starting mo-

tor it will be understood that the double reduction or indirect method may be employed. Further while I have shown the so-called inboard type of drive in which the driving member or pinion moves toward the motor when going into mesh with the engine member, the outboard type in which the driving member or pinion moves outwardly at such time may be employed.

As shown the prime mover is an electric motor 1 having an extended armature shaft 2 extending through the end plate 3 of the motor frame with a bearing therein and having an outer bearing at 4 in the outer end of a housing 5, which is attached by the screws 6 to the bracket 7. This bracket is in the present instance a part of the frame of the automobile engine whose fly wheel 8 is exposed to the drive. The armature shaft which is the drive shaft of the drive or transmission also has an intermediate bearing 9 formed in the extended outer end of the bracket 10 projecting from the end plate 3 of the motor. This bearing 9 supports the enlarged portion 11 of the driving shaft 2, which portion forms a stop for the pinion as hereinafter described.

Upon the intermediate portion of the drive shaft is mounted a screw shaft 12, which has at its outer end a driven head 13. Upon the screw-threaded portion of this shaft is screw-threaded the driving member which is here in the form of a pinion 14, adapted to mesh with the gear of the flywheel 8.

The driven head 13 of the screw shaft is operatively connected with a driving head 15 through the medium of a coiled spring 16 whose opposite ends are anchored to such heads respectively by the studs 17 and 18. The screw shaft and its head 13 are not secured to the driving shaft 2 but float thereon, but the driving head 15 is secured to such shaft 2 so that its motion may be communicated thereto and also the motion or rotation of the shaft 2 may be communicated to such head 15. This driving head 15 is provided with an outwardly extending sleeve 19 which has gear teeth 20 formed thereon. These gear teeth 20 mesh with the rack teeth 21 formed toward the lower end of a plunger 22 which is guided by and adapted to slide vertically in the housing 5. Normally this plunger is in an upward position with

its teeth in mesh with the teeth 20 of the driving head, such position being normally maintained by the coiled spring 23 bearing respectively against the housing 5 and the head 24 at the top of the plunger. This plunger is limited in its upward movement by means of a collar 25 secured to the lower end of the plunger by the cotter pin 26.

The plunger is so positioned that when it is depressed to its lowermost position as shown by dotted lines in Fig. 1, it will contact and depress the movable element 27 of a suitable electric switch 28 with the result that when such element is so depressed the electric current will be supplied through the wires 29 to the motor, thereby operating such motor.

Describing a cycle of operation and beginning with the parts in their normal position shown in Fig. 1, the first step is the depression of the plunger 22 with the result that the driving head 15 is rotated and the screw shaft 12 likewise rotated. Thereupon the pinion 14 will be caused to automatically advance longitudinally of such shaft and into mesh with the fly wheel 8. By preference the construction is such that the initial movement of the plunger causes only a partial mesh of the pinion 30 with the fly wheel gear instead of a full mesh, such full mesh being automatically effected. When the pinion is thus in partial mesh, the switch 28 will be operated and the motor rotated, whereupon full mesh of the pinion will be effected and the drive thereupon operated by the power of the motor. As soon as the engine starts on its own power the pinion 14 is automatically demeshed from the fly wheel and returned to normal position as shown.

The plunger 22 and the switch 28 are so positioned and related one to the other that when the switch 28 is operated and the motor started the pinion 14 is in partial mesh with the fly wheel, and the rack teeth have fully cleared the teeth 20 of the driving head, which teeth now occupy the space 30 in the cutaway portion on one side of such plunger. The switch is operated at the fully depressed position of the plunger and when such plunger is permitted to rise even a short distance the switch 28 is opened and the current cut off from the starting motor. However, at this time the plunger 55 cannot necessarily rise to its normal position because the driving shaft and the teeth 20 may then be rotating, but as soon as such parts cease to rotate the plunger 22 will be permitted to rise, at which time it will 60 rotate the driving head 15 in the opposite direction.

In Figs. 3 and 4 I have shown a modified form of construction in which provision is made for the return of the plunger to normal position even during the operation of

the drive or transmission, that is, during the time of the rotation of the driving head 15. Such provision consists of the employment between the teeth 20 and the driving head 15 of a one-way clutch. Describing 70 the construction shown, the driving head and its sleeve are made in two separate parts, the driving head being shown at 31 and the sleeve with its gear teeth at 32. Between these two parts there is located a 75 one-way clutch, one member 33 of which is secured to the sleeve 32 and the other 34 secured to the head 31. This clutch is of the common type employing a suitable number of balls 35 located in inclined recesses 36 in one of said members, and adapted to form the driving connection between such members when rotating in one direction only. It is evident that after the plunger has been depressed for the performance of 80 its functions it is free to rise at the moment when the operator releases his pressure thereon.

As above stated, it is preferred that the manual means should give only a partial 90 mesh leaving it to the motor to complete the mesh. This is for the purpose of giving the motor a running start instead of imposing a full load thereon immediately upon the closing of the switch, as would be the 95 case if the pinion were then in full mesh. Obviously, the manual means could be adopted to give such full mesh but this is not preferred.

I claim:

1. In an engine starter the combination of an electric motor and its electrical connections including a switch, a rotatable shaft driven by the motor, a driving member adapted to engage a member of the engine to be started and mounted on the shaft for automatic longitudinal movement thereof when rotated to thereupon engage such engine member and for rotary movement therewith when in engagement with the engine member, and manually operated means for initially rotating the shaft to cause said driving member to so move longitudinally and thereby cause engagement of said members and for subsequently closing said switch 100 to start the motor.

2. In an engine starter the combination of an electric motor and its electrical connections including a switch, a rotatable shaft driven by the motor, a driving member 110 adapted to engage a member of the engine to be started and mounted on the shaft for automatic longitudinal movement thereof when rotated to thereupon engage such engine member and for rotary movement therewith when in engagement with the engine member, and manually operated means for initially rotating the shaft to cause said driving member to so move longitudinally and thereby cause engagement of said members 115 and for subsequently closing said switch 120 to start the motor.

bers and for subsequently closing said switch to start the motor, such means including a reciprocating member operatively connected with the shaft and adapted to cooperate with the switch.

3. In an engine starter, the combination of an electric motor and its electrical connections including a switch, a rotatable shaft driven by the motor, a driving member adapted to engage a member of the engine to be started and mounted on the shaft for automatic longitudinal movement thereof when rotated to thereupon engage such engine member and for rotary movement therewith when in engagement with the engine member, and manually operated means for initially rotating the shaft to cause said driving member to so move longitudinally and thereby cause engagement of said members and for subsequently closing said switch to start the motor, such means including a pinion connected with the shaft, a reciprocating rack cooperating with the pinion to rotate it and the shaft said switch being disposed in the path of travel of the rack and operated thereby after it has rotated the pinion.

4. In an engine starter, the combination of an electric motor and its electrical connections including a switch, a rotatable shaft driven by the motor, a driving member adapted to engage a member of the engine to be started and mounted on the shaft for automatic longitudinal movement thereof when rotated to thereupon engage such engine member and for rotary movement therewith when in engagement with the engine member, and manually operated means for initially rotating the shaft to cause said driving member to so move longitudinally and thereby cause engagement of said members and for subsequently closing said switch to start the motor, such means including a reciprocating member operatively yieldingly connected with the shaft and adapted to cooperate with the switch.

5. In an engine starter, the combination of an electric motor and its electrical connections including a switch, a rotatable shaft driven by the motor, a driving member adapted to engage a member of the engine to be started and mounted on the shaft for automatic longitudinal movement thereof when rotated to thereupon engage such engine member and for rotary movement therewith when in engagement with the engine member, and manually operated means for initially rotating the shaft to cause said driving member to so move longitudinally and thereby cause engagement of said members and for subsequently closing said switch to start the motor, such means including a reciprocating member operatively connected with the shaft and adapted to

cooperate with the switch, and a spring drive between such reciprocating member and the shaft.

6. In an engine starter drive the combination of a motor driven rotatable shaft, a pinion mounted thereon for longitudinal movement thereof and for rotary movement therewith, such pinion being adapted to mesh with a member of the engine to be started, and manually operated means for initially rotating such shaft to cause partial mesh between the pinion and the engine member and for subsequently closing the switch to start the motor and rotate the shaft to automatically complete the mesh and then to rotate the pinion to start the engine.

7. In an engine starter drive, the combination of a motor-driven rotatable shaft, a driving member mounted thereon for automatic longitudinal movement thereof and for rotary movement therewith, manually operated means for rotating such shaft to cause initial automatic longitudinal movement of the driving member, and means for automatically completing the longitudinal movement of the driving member.

8. In an engine starter drive, the combination of a motor driven rotatable screw shaft, a driving member screw-threaded thereon for automatic longitudinal movement thereof and for rotary movement therewith, manually operated means for rotating such shaft to cause initial automatic longitudinal movement of the driving member, and means for automatically completing the longitudinal movement of the driving member.

9. In an engine starter drive, the combination of a motor, a rotatable shaft driven thereby, a driving member mounted on the shaft for automatic longitudinal movement thereof and for rotary movement therewith, manually operated means for rotating such shaft to cause such automatic longitudinal movement of the driving member, and a one-way clutch between such means and shaft, said means and motor operating successively in the same starting operation.

10. In an engine starter drive, the combination of a motor, a rotatable shaft driven thereby, a driving member mounted on the shaft for automatic longitudinal movement thereof when such shaft is rotated and for rotary movement therewith, a plunger operatively connected with the shaft to rotate it, and a one-way clutch interposed in the connection between the plunger and shaft, said plunger and motor operating successively in the same starting operation.

11. An engine starter drive including a motor driven rotatable shaft, a driving member mounted thereon for automatic longitudinal movement thereof and for rotary movement therewith, a manually operated

member, and means between such latter shaft, a hollow screw shaft mounted thereon and driven thereby, a driving member screw-threaded on the screw shaft, a driving head secured to the driving shaft and operatively connected with the screw shaft, manually operated means for initially rotating such head, consisting of a pinion connected with the head and a plunger provided with a rack meshing with such pinion, and means for automatically further rotating said head.

12. In an engine starter drive, the combination of a motor driven rotatable shaft, a driving member mounted thereon for automatic longitudinal movement thereof when rotated to thereupon engage a member of the engine to be started, and for rotary movement therewith, a driving head operatively connected with the shaft, a pinion connected with such head, manually operated means for initially rotating the pinion and thereby rotating the shaft, and means for automatically further rotating said shaft.

13. In an engine starter drive, the combination of a motor, a rotatable shaft driven thereby, a driving member mounted on the shaft for automatic longitudinal movement thereof when rotated to thereupon engage a member of the engine to be started and for rotary movement therewith, a driving head operatively connected with the shaft, a pinion connected with such head, and manually operated means for rotating the pinion thereby rotating the shaft, such means consisting of a plunger provided with a rack meshing with the pinion, said means and motor operating successively in the same starting operation.

14. In an engine starter drive, the combination of a motor driven rotatable shaft, a driving member mounted thereon for automatic longitudinal movement thereof when rotated to thereupon engage a member of the engine to be started and for rotary movement therewith, a driving head operatively connected with the shaft, a pinion, a one-way clutch connecting the head and pinion, and manually operated means for rotating the pinion and thereby rotating the shaft.

15. In an engine starter drive, the combination of a motor driven rotatable driving shaft, a hollow screw shaft mounted thereon and driven thereby, a driving member screw-threaded on the screw shaft for automatic longitudinal movement when such shaft is rotated, a driving head secured to the driving shaft and operatively connected with the screw shaft, manually operated means for initially rotating such head, and means for automatically further rotating said head.

16. In an engine starter drive, the combination of a motor driven rotatable driving

shaft, a hollow screw shaft mounted thereon and driven thereby, a driving member screw-threaded on the screw shaft, a driving head secured to the driving shaft and operatively connected with the screw shaft, manually operated means for initially rotating such head, consisting of a pinion connected with the head and a plunger provided with a rack meshing with such pinion, and means for automatically further rotating said head.

17. In an engine starter, the combination of a motor driven driving shaft, a casing having bearings for such shaft, a hollow shaft mounted on the driving shaft and driven thereby, a driving member mounted on the hollow shaft for automatic longitudinal movement thereof and rotary movement therewith, and manually operated means for rotating the hollow shaft to cause such automatic longitudinal movement of the driving member, such means being mounted in said casing.

18. In an engine starter, the combination of a motor driven driving shaft, a casing having bearings for such shaft, a hollow shaft mounted on the driving shaft and driven thereby, a driving member mounted on the hollow shaft for automatic longitudinal movement thereof and rotary movement therewith, and manually operated means for rotating the hollow shaft to cause such automatic longitudinal movement of the driving member, such means consisting of a plunger operatively connected with the latter shaft and mounted to reciprocate in such casing.

19. In an engine starter drive, the combination of a motor driven rotatable shaft, a driving member mounted thereon for automatic longitudinal movement thereof and for rotary movement therewith, a housing supporting said shaft, and manually operated means mounted in such housing and operatively connected with the shaft for rotating it to cause such automatic longitudinal movement of the driving member.

20. In an engine starter device, the combination of an engine member, a motor, a rotatable shaft driven by said motor, a driving member mounted thereon for automatic longitudinal movement thereof and for rotary movement therewith, and manually operated means for rotating said shaft to move said driving member into initial engagement with said engine member, said motor automatically completing the engagement of said driving member and said engine member.

WILLIAM L. McGRATH.
